SIGNAL FOR BROODERS

Frank Mockelmann, Millard, Nebr.

Application May 22, 1931. Serial No. 539,392

4 Claims. (Cl. 200—140)

This invention relates to a signaling device for brooders, and more particularly to a thermostatically operated warning signal therefor.

An object of the invention is to provide signaling means whereby an operator stationed at a distance from the brooder may be apprised of the varying temperature conditions in the brooder, the former being placed at an appreciable distance from the operator.

Another object of the invention is to provide warning means in case the brooder ceases to be properly heated, and the operator will at once be warned of the thermic changes therein, and will have ample time for resetting the brooder heater governing the temperature of the latter before harm is done the chicks.

A still further object of this invention is to provide signaling means whereby the operator thereof will be warned in advance should the temperature rise too high; thus eliminating the danger of fire within the brooder, or building in which the brooder is housed.

Other objects and advantages of this invention will be apparent from the drawings and detailed description thereof:

In the drawings:

Figure 1 is a vertical section of a brooder showing the signaling device as positioned therein and illustrating in a diagrammatic form the connections between the same and an adjacent house where the alarm is to be sounded.

Figure 2 is a detail side elevation of the thermostat, showing the electric contacts of the device.

Figure 3 is an end elevation of Figure 2, and Figure 4 is a horizontal section taken on the lines 4—4 of Figure 2.

Referring to the drawings, 10 designates a brooder with the usual heater 11. A thermostat 12 rests on an arm 13, connected to one end of the stand 14, which has an upright 15 at its other end. The stand 14 has on said first end a down turned leg 16 secured to the brooder 10 by a keeper 17. The stand 14 at said opposite end is secured to the upright 15 by a keeper 18, a hollow bolt 19 extending therethrough and secured by nuts 20. The lower end 21 of the upright 15 is flanged and is adapted to rest on the base of the brooder 10, and secured thereto by a keeper 22. The lower end of the upright 15 is so constructed as to in no way interfere with the heat or temperature in the brooder 10.

A metal arm 23 is connected movably at 24, and is moved by the diaphragm 12 by means of an adjustable screw 25. An adjustable movable

weight 26 is fitted on the metal arm 23, providing a counter balancing weight which controls the operation of the diaphragm 12 under changes in temperature.

The balancing weight 26 has a knife portion 27 which selectively engages between teeth 28 of the bar 23 retaining the weight thereon in any desired position.

The thermostat 12 is preferably composed of a double diaphragm and is anchored by a pin 29 to the arm 13 and stand 14. The bolts 30 keep the arm 13 rigidly on the stand 14. The arm 13 has a hook 31 on its outer end the purpose of which will be explained further on.

The outer end of the arm 23 is provided with movable contacts 33 and 34 which are retained in insulated relation by a bolt 35 and nut 36.

The upright 15 still further has an upper outstanding arm 38 secured thereto by nuts 39 in an insulated manner, insulation shown at 40.

An adjustable set screw 41 is provided in the arm 38 and is adapted to contact with said contact 33 at given times.

The arm 38 has a sliding bolt 42 with a limiting nut 43 and is urged downward, by a spring 44 towards the bolt 35. When too sudden a temperature change takes place in the brooder 10, the double diaphragm is correspondingly actuated, and if the temperature fluctuates, but several degrees the spring 44 prevents the closing of a circuit, permitting a few degrees of fluctuation without giving a warning. An adjustable contact screw 46 is threaded through a lower bracket 47, secured to the upright 15 by nuts 48, insulation being at 49.

In order to obviate the upsetting of the upright 15, side arms 50 are secured thereto, held in this position by keepers 51 and in turn to the base of the brooder 10 by bolts 52.

The upright 15 carries midway and crosswise a pin 53 on which a screen 54 is carried as in Fig. 1. The inner end of the screen 54 rests on the hook 31. The screen 54 wards off chicks from coming in contact with the device.

56 designates the house of the operator, situated at a remote distance from the brooder 10, and in which means are employed, signaling means, such as a red or white light, but preferably a buzzer 57 and a bell 58 electrically connected by a wire 59, the electricity so needed is obtained from the usual house current of 110 volt current, or a battery 60 connected at one side to the wire 59 and having a ground wire 61 which extends to the brooder, through the hollow bolt 19 and to the bolt 35 which is in elec-

trical engagement with the movable contacts 33 and 34.

If the temperature within the brooder 10 has risen to too great a degree the thermostat 12 expands, thus causing the arm 23 to be raised by means of the action thus transmitted to the adjustable screw 25, said action causing the insulated head 35 of the bolt to come in contact with the insulated head of the opposed bolt 42 and spring 44 mounted thereon, and if the temperature rises sufficiently the resistance of the spring 44 is overcome, whence the contact 33 establishes electrical connection with the adjustable screw 41 whereby the circuit is closed through the wire 62 and to the bell 58, causing the same to sound a warning which indicates the temperature within the brooder 10 has risen to too high a degree and the stove or lamp 11 needs adjusting. Similarly, if the temperature within the brooder 10 falls because the stove 11 ceases to function, the thermostat 12 contacts and allows the arm 23 to fall or be lowered whereby the contact member 34 will be caused to form an electrical connection with the set screw 46 and the contact thus formed closes the electrical conductor 63 to the buzzer 57, actuating the same and causing the occupant or operator to be informed that the temperature within the brooder has fallen and that the chicks are in danger of freezing.

It will be apparent from the description that the operator is notified at once of thermic changes within the brooder 10, and such thermic changes indicate a rise or lowering of temperature therein.

The elongated upright 15 is merely for the purpose of protecting the wires or aiding in the carrying of the wires upwardly.

In order to adjust the mechanism for the most efficient or selected results the operation is as follows:

A common thermometer is hung in the brooder in a visible position in order that the temperature may be readily noted.

Assuming that the temperature reading is 70 degrees the set screw 46 is adjusted upwardly and the set screw 25 is so adjusted that a contact is established between the set screw 46 and the electrode 34; whereupon an alarm will sound or signal be caused at 70 degrees of temperature.

Assuming that the operator desires an alarm or signal to be caused should the temperature arise in the brooder to 100 degrees of heat the mechanism is adjusted as follows:

Sufficient heat is caused to be generated in the brooder until the thermometer reads 100 degrees and at this time the bellows 12 will greatly expand and the beam or lever 23 in an extreme swung upward position. The operator now moves the screw 41 downward until its head or lowermost point is slightly higher than the lowermost point of the resiliently and yieldably mounted bolt or bumper post 42.

From the foregoing description it is thought obvious that a signal for brooders constructed in accordance with my invention is particularly well adapted for use by reason of the convenience and ease with which it may be assembled and operated, and it will also be obvious that my invention is susceptible to some change and modification without departing from the principles and spirit thereof, and for this reason I do not wish it to be understood as limiting myself to the precise arrangement and formation

of the several parts herein shown in carrying out my invention in practice except as herein claimed.

What is claimed is:

1. A circuit closer, comprising a thermostat, a pivoted lever arranged above the thermostat, adjustable supporting means between the lever and the thermostat for supporting the lever from the thermostat at a predetermined normal position, adjustable means on the lever for steadyng the same, movable contacts carried by the lever, fixed contacts spaced from the lever for engaging the movable contacts when the lever is swung through a predetermined distance, and cushioning stop mounted independently of the lever and in advance of a fixed contact to yieldingly arrest the movement of the lever when subjected to sudden vibration and prevent closing of the contacts except by positive movement of the lever. 95

2. A circuit closer, comprising a pivoted lever, a thermostat, adjustable means between the lever and the thermostat for moving the lever upon the operation of the thermostat, opposed movable contacts carried by the lever, opposed fixed contacts spaced at opposite sides of the lever in line with the movable contacts, and a yieldable stop device disposed in advance of one of said fixed contacts for engagement with the lever to prevent engagement of the fixed and movable contacts incident to vibration of the lever toward said fixed contact. 105

3. A circuit closer, comprising a frame, a thermostat mounted on the frame and secured thereto at its lower end, a lever pivotally mounted on the frame above the thermostat, a set screw carried by the lever for adjustably engaging the thermostat to support the lever therefrom, a weight mounted for longitudinal adjustment on the lever to steady the same and vary the resistance of the lever to operation by the thermostat, upper and lower movable contacts carried by the lever, upper and lower fixed contacts mounted on the frame in spaced relation to the lever, and spring means for engaging the lever upon vibration thereof to prevent closing of the contacts except upon the steady movement of the lever in either raised or lowered positions. 115

4. A circuit closer for use in signal circuits and the like, comprising a frame having an upright post at one end and an overhanging arm at its opposite end, fixed contacts mounted for adjustment upon said post and disposed in vertically spaced apart relation thereon, a yielding buffer carried by the post in advance of the upper contact thereof, a lever pivotally mounted at one end upon said overhanging arm and extending horizontally toward said post, movable contacts mounted upon the opposite sides of the lever at its free end, said lever supporting the movable contacts between said fixed contacts and in position to alternately engage the same upon the rise and fall of the lever and thermostatic device mounted on the frame beneath said lever, adjustable means between the lever and said thermostatic device for determining the relative normal position of the free end of the lever with respect to the thermostatic device and a weight adjustably mounted on the lever for tensioning the latter against the thermostatic device. 120
